COMBINATION SLIDE, SEESAW, AND JUMPING BOARD

Filed March 11, 1927

Inventor:

Matilda Remy,
daughter of James Remy, my
attys.

UNITED STATES PATENT OFFICE

MATILDA REMY, OF WELLESLEY, MASSACHUSETTS

COMBINATION SLIDE, SEESAW, AND JUMPING BOARD

Application filed March 11, 1927. Serial No. 174,439.

This invention relates to a device which is intended to furnish healthful amusement, exercise, and recreation for children.

Among the objects of the present invention, 5 is to provide a device which is of a simple and sturdy construction, which is adjustable for children of various sizes, which may be easily and rapidly assembled and disassembled, and which is capable of serving a multiplicity of 10 uses, and more especially as a seesaw, a walking, balancing or jumping board, and a slide.

The device of the present invention consists in general of one or more boards constructed for assembly with one or more standards 15 which are provided with a plurality of supporting rungs, any one or more of which may be selectively engaged by the boards, as may be desired.

Further features and advantageous details 20 and combination of parts will appear from a more complete description of an embodiment of the device shown in the accompanying drawings, in which

Figure 1 illustrates in perspective a stand- 25 ard.

Figure 2 is a similar view showing a board.

Figure 3 represents a side elevation partly in section, of the device assembled with one standard, as a seesaw.

30 Figure 4 is a similar view, showing the device assembled with two boards and two standards, as a walking board.

Figure 5 represents a side elevation, partly broken away, of a board assembled with one 35 standard, as a slide.

Figure 6 is a detail section on the line 6—6 of Figure 3.

Referring to the drawings, the standard 40 designated as a whole as A, preferably constructed of wood, comprises a pair of spaced supporting bases in which are fixed a pair of posts 2, which are bridged transversely and maintained in spaced relationship by a plurality of spaced supporting rungs 5, whose 45 ends are fixed therein. Each of the posts is maintained rigidly in place by a triangularly-shaped brace 3, fastened at its apex portion 3^a to the post and at its base portions 3^b to the base 1. The bases are also maintained rigidly 50 in place by fastening thereto a straddle piece

4, extending transversely from one base to the other and provided at its ends with downwardly projecting portions 4^a, which engage the outer face 1^a of the bases, to prevent lateral separation thereof.

55 A board designated as 6 is shown provided at its under side, near its ends and at its center, with a pair of spaced cleats 8, forming between them recesses 9 which may be made to engage selectively any one of the rungs 5 of the standard A. As shown in Figure 3, 60 wherein the device is used as a seesaw, the top rung is engaged in the recess formed at the central portion of the board. If it is desired that the device accommodate smaller 65 children, the board is placed on a lower rung.

The board when assembled with a pair of standards, as shown in Figure 4, may serve as a walking, balancing, jumping board, or bench. The board as thus assembled is shown 70 with the middle rungs of each of the standards fitted into the recesses at the ends of the board, but if desired the board may be assembled with the top rungs as indicated in dotted line, or with the bottom rungs. When 75 the top or middle rungs are used, preferably another similar board 7 is assembled with the bottom rungs so as to maintain the device more rigidly assembled.

As shown in Figure 5, the board is engaged 80 at one end on one of the rungs, and rests on the ground at the other end, thus constituting a slide.

85 A device such as described, because of its multiple uses, in addition to aiding physical development, arouses the interest of children and stimulates imaginative play.

Having thus described an embodiment of 90 this invention, it is evident that various changes might be made without departing from the spirit or scope of invention as defined by the appended claims.

What I claim is:

1. In a device of the class described, the combination with a pair of standards, each of which is provided with a plurality of transversely extending rungs, of a pair of horizontal, flat-faced boards provided with recesses on their under sides near their ends, in which recesses the rungs of said pair of stand- 100

ards loosely engage each of said boards at different levels, the board at the lower level serving to maintain the device in rigid assembly.

5 2. In a device of the class described, the combination with a pair of standards, each of which is provided with a pair of spaced supporting bases, uprights fixed to said bases, and a plurality of rungs transversely bridging said uprights, of a pair of horizontal, flat-faced boards provided with recesses on their under sides near their ends, in which recesses 10 said rungs in pairs loosely engage each of said boards at different levels, the board at the 15 lower level serving to maintain the device in rigid assembly.

In testimony whereof I have affixed my signature.

MATILDA REMY.
